UNITED STATES PATENT OFFICE

JOHN Q. HOLMES, OF ANDERSON, INDIANA, ASSIGNOR TO DELCO-REMY CORPORATION, OF ANDERSON, INDIANA, A CORPORATION OF DELAWARE

APPARATUS FOR SORTING COMMUTATOR SEGMENTS

Application filed November 29, 1929. Serial No. 410,453.

This invention relates to the manufacture of commutators for dynamo electric machines, and particularly to commutators having segments which are wedge-shaped in cross section.

In the manufacture of commutators, especially where automatic machinery is employed for assembling the commutator parts, it is a decided advantage to have all of the commutator segments of the proper length so that the operators of the automatic machines will not be required to stop the machinery and remove segments which are short or over size. Therefore, it is one of the objects of the present invention to provide apparatus for automatically sorting the bars which are too short or too long from those which are of the proper length. The disclosed embodiment of the present invention includes a hopper into which a quantity of segments are placed promiscuously and from which segments are fed in orderly fashion to a device which automatically sorts bars of improper length from those of proper length.

Further objects and advantages of the present invention will be apparent from the following description, reference being had to the accompanying drawings, wherein a preferred embodiment of one form of the present invention is clearly shown.

In the drawings:

Fig. 1 is a perspective exterior view of a hopper feed mechanism embodying the present invention and an associate mechanism which receives segments from the hopper feed and automatically sorts the segments of proper length from those of improper length.

Fig. 2 is a fragmentary, perspective view looking down into one of the hoppers and shows segments which have been elevated from the bottom of the hopper and which appear sliding down a chute which causes them to slide endwise rather than sidewise, and which also shows a gate mechanism which permits the segments to pass only when they are presented to the gate in a predetermined manner.

Fig. 3 is a diagrammatic view of the mech-

anism for driving the hopper feed and mechanism associated therewith.

Fig. 4 is a fragmentary plan view.

Fig. 5 is a fragmentary, side view partly broken away.

Fig. 6 is a sectional view on the line 6—6 of Fig. 4.

Fig. 7 is a sectional view on the line 7—7 of Fig. 5.

Fig. 8 is a full scale sectional view on the line 8—8 of Fig. 6.

Fig. 9 is a full scale sectional view on the line 9—9 of Fig. 6.

Fig. 10 is a fragmentary, plan view of that portion of the apparatus shown in Fig. 9, looking in the direction of the arrow 10.

Fig. 11 is a fragmentary, plan view of the sorting apparatus partly in section, the section being on the line 11—11 of Fig. 12.

Fig. 12 is a fragmentary, sectional view on the line 12—12 of Fig. 11.

Fig. 13 is a fragmentary, sectional view on the line 13—13 of Fig. 11.

Fig. 14 is a plan view of the mechanism for driving the sorting device shown in the preceding figures.

Fig. 15 is a sectional view taken on the line 15—15 of Fig. 14.

Hopper feed mechanism

Referring to Fig. 1, numerals 20 designate supporting posts or upright angle bars to which are secured, by screws 21, a pair of hoppers 22 which are secured together in spaced relation by a pair of channel bars 23 attached by screws 24. Since the hoppers and feeding mechanism, associated with each, are duplicates, only one feeding mechanism will be described.

The mechanism comprises chiefly means for elevating segments from the bottom of the hopper to a location near the top thereof, a chute which receives segments from the elevating means and which permits the segments to pass by gravity to a lower level during which the segments are caused to slide for the most part finally endwise, and a gate mechanism which permits the segments to pass only when they are presented in a predetermined relation to the gate and

which removes from the chute the segments which will not pass the gate.

The elevating mechanism comprises a rotatable bucket wheel 30 which includes a web 31 merging with a hub 32 mounted upon a drive shaft 33 which is supported in a bearing 34 mounted in a suitable recess in an end cover 35 attached to the hopper 22 by screws 21 and 36, and in a suitable recess provided by a plate 37 attached by screws 38 to the hopper end wall 35. The web of the wheel 30 merges with an annular flange 39. A plurality of vanes 40 extend from the web 31 and the flange 39 and provide buckets or pockets 41 for receiving segments indicated by numeral 25 in the bottom of the hopper as shown in Fig. 2. The segments may pass through an arcuate opening 42 in the hopper side wall 35 when passing into the buckets 41. The shape of this opening 42 is shown particularly in Fig. 5 and is bounded by the concentric arcuate line KL and MN joined by the radial lines LM and NK. The plate 37 is provided with a flange 43 which prevents the segments dropping from the buckets when the vanes move into the position indicated at 40a, 40b and 40c, the direction of rotation being clockwise as viewed in Fig. 5. The flange 43 of the plate 37 merges above the shaft 33 with a dished flange 44 indicated by the curved line in Fig. 5. As the pockets 41 move into a position nearly vertically above the shaft 33, the segments therein fall upon the flange 44 and upon a chute 50 which permits the segments 25 to slide downwardly upon a plate 51 which is curved in both directions in order to direct the movements of the segments into a direction which is transverse to the direction of movement of the segments as they move along the chute 50. In order to be sure that the pockets empty upon the chute 50 there is provided a scraper 52 attached by rivets 53 to the end plate 35 and bent so that its free end 54 extends into the opening 42 and hence into the pockets 41. The elevator is of such size that there will be a great surplus of segments deposited upon the chute 50. The contours of the chute at different vertical cutting planes parallel to the end cover 35 are represented by lines ab, cd, and ef in Fig. 5 denoting the cross sectional contours at lines a'b', c'd', and e'f' respectively in Fig. 4. The portion of the chute 50 adjacent the upper end near the opening 42 is large enough to accommodate most of the segments which are deposited upon the chute, but the lower end of the chute is relatively narrow in order that only the segments which slide endwise will be retained upon the chute 50. It will be noted from Fig. 2 that the upper portion of the chute 50 is provided with a flange 55 which terminates in a finger 56 approximately where the chute 50 abruptly narrows down as indicated by numeral

57 in Fig. 2. The purpose of the flange 55 is to confine a large number of segments upon the chute 50 at the upper end thereof so as to increase the possibility of having a sufficient number of segments which will move endwise along the chute rather than sidewise. The flange 55 terminates in the fingers 56 so as to permit those segments which tend to slide laterally to drop from the chute. The curved plate 51 directs the segments upon a second chute or shelf bar 60 attached by screws 61 to the side wall 62 of the hopper 22. The wall 62 also receives the screws 63 which support the plate 51. The chute 60 provides an inclined surface 64 which receives the commutator segments 25 which slide endwise down the chute 60. The wider edge of the segment bears against an inclined surface 65. If the segments do not slide substantially sidewise down the chute 60, they will engage with a flange 66 of an ejector plate 67 attached by screws 68 to the chute bar 60. The flange 66 is spaced from the surface 64 at such a distance that two superposed segments might slide down the surface 64, the upper segment being represented by the dot and dash lines 25a, in Fig. 9. After passing the ejector plate 67, the segments pass through a gate which consists of a rotating wheel 70 provided with a plurality of curved vanes or paddles 71 and a toothed disc 72. The wheel 70 is mounted upon a shaft 73 and rotates in a clockwise direction as indicated by arrows 74 in Fig. 6. The paddles 71 are so spaced from the surface 64, as shown in Fig. 6, that a segment will pass the gate wheel 70 only when the segment slides with its broader edge against the chute surface 65. In case the segment slides with its broader edge remote from the surface 65 as indicated at 25b in dot and dash lines in Fig. 8, that segment will be engaged by a paddle 71 and will be thrown slantly upward and thus ejected from the chute 60. In case a segment should slide down the chute sidewise instead of endwise as indicated at 25c in Fig. 6, the toothed disc 72 will engage that segment and eject it from the chute.

It is therefore apparent that the segments which pass the gate wheel 70 when sliding down the chute 60, are only those segments which slide endwise and which are arranged in a predetermined order, namely, with their wider edges against the chute surface 65. Consequently, the segments which pass from the ends of the chute 60, as viewed in Fig. 1, all pass in orderly end-to-end relation. After the segments pass the chute 60 they are conducted through tubular conduits of somewhat rectangular cross section 80 which make a quarter turn in going from the distance from the ends of the chute 60 to the bar sorting mechanism 200 to be described.

The mechanism for operating the shafts 33 and 73 will now be described with particular reference to Fig. 3. The posts 20 support a suitable platform which carries a driving motor 90 operating a shaft 91 which carries worm wheels 92 and 93 meshing with worm gears 94 and 95 respectively, attached to shafts 96 and 97 respectively. The shaft 96 drives a sprocket wheel 98 connected with a sprocket wheel 99 by a sprocket chain 100. The wheel 99 is mounted loosely on shaft 33 and carries a shear pin 101 adapted to drivingly engage a lug 102 provided by a disc 103 having a hub 104 pinned to the shaft 33. The hub 105 of the sprocket wheel 99 is confined between the disc 103 and a collar 106 also pinned to the shaft 33. If, due to a jamming of segments in the elevator wheel 30, or for any other reason, the torque required to turn the shaft 33 becomes excessive, the pin 101 will be sheared off adjacent the lug 102, then the transmission of power from the motor to the shaft 33 will be interrupted, thus protecting the machinery from further injury. The shaft 97 drives a pulley wheel 110 connected by a belt 111 with a pulley wheel 112 attached to a shaft 73.

Sorting apparatus

Fig. 1 shows two similar chutes 80 and 80a which feed segments 25 from the hopper feed mechanism just described to two similar sorting devices generally designated 200 and 200a respectively. As both devices are similar in construction, the device 200 will be the only one described in detail. The apron 120 includes a table portion 201 attached by screws 202 to a frame 203, shown in Fig. 12. Frame 203 is supported by a pipe pedestal 204 threaded into a base plate 205. Frame 203 includes a circular table portion 206, upon which the segments 25 are pushed from the end of the chute 80 to an aperture 207, having portions 208 and 209 differing in width. The portion 208 which extends arcuately from a radial line ab to a radial line cd and shown in Fig. 13, is less in width than the aperture portion 209 extending from the radial line cd to the radial line ef and shown in section in Fig. 12. The segments 25 are pushed from the end of the chute 80 in a counterclockwise direction by the toothed wheel 210 providing notches 211, each adapted to receive a segment as it falls by gravity from the lower end of the chute 80, and slides along the table 206 into a notch 211, due to the momentum it has gained while descending through the chute. The trailing edges of the teeth 212 which separate the notches 211, are curved as indicated at 213. As soon as the last segment 25 received by notch 211 moves away from a segment located at the lower end of the chute 80, that segment will be released and caused to de-

scend and move against the curved edge 213 of the teeth 212. The curved edge permits the segment to be directed into the end of the notch 211. As the segments 25 are pushed along by the toothed wheel 210 toward the aperture 207, they are retained in the notches 211 by an arcuate sheet metal guard 215, which confines the segment within the notches at the toothed wheel 210 but not with sufficient pressure to resist the dropping of the segments through the aperture 207. It is apparent that those segments which are too short will drop through the orifice portion 208 and into a delivery chute 218 while those of proper length will drop through the aperture portion 209 and will be received by a delivery chute 219. Those longer than required will remain on the table after passing in a counterclockwise direction from the aperture 207 and may be removed by the operator.

The toothed wheel 210 is attached by screws 220 to the flange 221 of a hub 222 of a hand wheel 223 connected by a key 224 with a shaft 225 journalled in bearings 226 and 227 provided by the frame 203. Between the bearings 226 and 227 there is located a pulley 230 attached to the shaft 225 by key 231. Pulley 230 is connected by belt 232 with a similar groove pulley 233, shown in Fig. 14, attached by a key 234 to a shaft 235 rotatably supported by a gear housing frame 236, shaft 235 is connected by a worm wheel 237 and a worm 238 with a shaft 239, which is connected by a coupling 240 with an electric motor 241.

The gear 234 connects the shaft 235 also with a gear 250 connecting with a similar gear 251, connected by a key 252 with a shaft 253 and a pulley 254. Pulley 254 is connected by a belt 255 with a pulley 238 connected with the shaft 256a which drives the sorting apparatus 200a. The only difference between the apparatus 200 and 200a is that the feeding wheel 210a rotates in a clockwise direction opposite to that of the wheel 210. This arrangement is preferred since the delivery tubes 218 and 219 may serve both sorting devices.

While the form of embodiment of the present invention as herein disclosed, constitutes a preferred form, it is to be understood that other forms might be adopted, all coming within the scope of the claim which follows.

What is claimed is as follows:

Apparatus for handling and assorting commutator segments which are wedge-shape in cross section, said apparatus comprising, in combination, a hopper for receiving the segments, a support upon which the segments are sorted said support having an aperture varying in width, a chute for delivering segments to the support and arranged to cause the segments to rest upon

their backs upon the support, means in the hopper for feeding segments in orderly relation to the chute, a notched disc receiving the segments in its notches as the segments issue from the lower end of the chute and rest upon the support, and means for rotating the disc to cause the segments to pass above the aperture in the support in order to sort the segments approximately according to length.

19 In testimony whereof I hereto affix my signature.

JOHN Q. HOLMES.
